MACHINE FOR PRODUCING FORM PIECES
FROM WET FIBROUS MASSBirger Fredrik Engelbrekt Nylander, Hernosand,
SwedenApplication January 8, 1936, Serial No. 58,046
In Germany May 27, 1935

1 Claim. (Cl. 92—62)

The present invention refers to machines for producing form pieces from wet fibrous mass for instance wood-pulp, which consist of an expansible, perforated core and a contractible, perforated form arranged outside of the former, which consist of pieces slidably connected with each other, and between which the mass is adapted to be led in and compressed, watered-down and dried by the expansion of the core and contraction of the form and the introduction of a warmed pressure-medium, for instance vapour. One of the objects of the invention is the provision of a device wherein the expansion of the core is caused by the pressure-medium through the introduction of the same into the core.

The contraction of the form is effected in that a conical ring or the like, which is provided with a part forming the roof of the form, is pressed over conical shoulders on the form. The parts of the core and the form are normally taken apart or compressed by spring arrangements in the core and outside the form.

The form is at its inside provided with outlet-channels for the water forming grooves, outside which perforated plates are arranged.

Under the interspace between the core and the form in the stand of the machine outlet-channels are arranged for the water.

An embodiment of the invention is shown in the annexed drawings. Fig. 1 shows the machine schematically in vertical longitudinal section in closed position. Fig. 2 shows the same in opened position. Fig. 3 shows the core in vertical section in contracted position. Fig. 4 shows the same in horizontal cross-section in contracted position. Fig. 5 shows the same in horizontal cross-section in expanded position. Fig. 6 shows the form in horizontal cross-section on one side in closed and on the other side in open position.

In the stand 1 the form 2 is arranged, which consists of four parts 3 (Fig. 6) movable toward and away from each other. The parts 3 of the form 2 are at their inside provided with vertical conduits 4, outside of which perforated plates 5 are fixed. The parts 3 are slidable in guide-bars in the stand 1 and are normally kept apart by means of springs 7 fixed at standards 6. The parts of the form are pressed against each other by means of a conical ring 8, which is fixed to the lower end of a plunger 9, which is actuated by hydraulic pressure. Over the conical ring 8 a part 10 is arranged, which on immersion of the ring 8 forms a roof for the parts 3 of the form 2, and which at its underside is shaped in a similar way as the inside of the parts 3, which at their

outside are provided with conical shoulders, against which the ring 8 presses in immersed position. In order that the part 10 shall not lie against the parts of the form 2 until these have been brought together, the ring 8 is connected with the plunger 9 by spring arrangements 11. In the form 2 the core 12 is arranged and fixed to a tube 13, which can be raised and lowered. The tube 13 is worked upon by hydraulic means and its interior is connected with a tube 14, through which steam can be introduced into the interior of the core 12. The mass is introduced through a tube 15 fixed to the underside of the stand 1, which tube is connected with a mass pump 16 and provided with a block-valve 17. Between the tube 15 and the stand there is besides arranged a slideable socket 18, which also is worked upon by hydraulic pressure. The core 12 consists of perforated plates 19 movable against and from each other, which are normally brought together by springs 20 arranged in the core. At the collision-places between the plates 19 angle-pieces 21 are arranged, which slide in guide-bars 22 fixed to the plates.

When a form piece is to be produced in the machine the ring 8 is first brought down to the position shown in Fig. 1 by hydraulic pressure, whereby the parts of the form are brought together. After this the valve 17 is opened, whereby the mass from the pump 16 is pressed into the tube 15 and enters the interspace between the core 12 and the form 2. When this interspace is filled with mass, which has partly been watered-down by the pressure, whereby the water partly goes out through the tube 13 and partly through the channels 23 in the stand 1, the pump 16 is stopped, and superfluous mass flows back to the pump. After this the valve 17 is closed and the socket 18 is brought up to the position shown by lines and dots, so that the interspace between the core 12 and the form 2 forms a closed room except for the perforations. Now overheated steam is led in to the tube 13 through the tube 14 and at the same time into the interior of the core 12 through the channels 24, whereby the steam presses the parts of the core 12 outwards and at the same time waters down, warms, dries and presses the form piece, what can take place, as the holes of the perforations are very small.

After the form piece has been watered down, dried and pressed to the desired degree, the supply of steam through the tube 14 is stopped, whereby the parts of the core 12 are contracted by the spring arrangements 20, so that the form

piece 25 is loosened from the core. The ring 8 is then brought up again, whereby the parts of the form 2 of the spring arrangements 7 are brought apart, so that the form piece 25 is loosened. Now the case 18 is brought upwards again, whereby the form piece is lifted up in the machine and can be removed from the same.

The form piece produced by this machine, which is adapted to work automatically, shows quite smooth surfaces inwardly as well as outwardly and has besides a dryness of at least 80%, a result, that cannot be arrived at by the machines known hitherto, where form pieces either get a rough surface or also have to be dried after the forming by an expensive and time-wasting procedure.

It is evident that the invention may be varied in many respects without departing from the idea on which it is based.

Having now described my invention, what I claim is:

A machine for producing pieces from a wet fibrous mass, comprising a core comprising a plurality of plates movable relatively to each other, whereby said core may be expanded and contracted, and resilient means connected with said plates for maintaining said core in the con-

tracted position, each of said plates being provided with small perforations; an expansible and contractible form, means adapted to engage said form to maintain the same in the contracted position while a form piece is being made, means maintaining said form in the expanded state when the second-mentioned means are devoid of contact with said form, means supplying a wet fibrous mass in the space between said core and said form, means connected with said form for removing a fluid therefrom, and means connected with said core for supplying a heated fluid under pressure into the interior of said core, whereby said fluid will press against the non-perforated portions of said plates to maintain said core in the expanded position and to heat and dry said wet fibrous mass, whereby a form-piece is produced, said core being movable by the first-mentioned means from the expanded position to the contracted position when the pressure of said fluid is diminished, and said form being movable from the contracted position to the expanded position when the second-mentioned means are moved out of contact with said form, thereby facilitating the removal of said form-piece. 25
